UNITED STATES PATENT OFFICE

HERBERT W. REEL, OF CHICAGO, ILLINOIS, ASSIGNOR TO UNITED STATES GYPSUM COMPANY, OF CHICAGO, ILLINOIS, A CORPORATION OF ILLINOIS

CEILING CONSTRUCTION

Application filed February 1, 1926. Serial No. 85,075.

This invention relates to improvement in building construction, but more particularly to the production of a monolithic or cast floor, roof, or ceiling which is continuous in 5 form under the supporting beams or floor framing, or it may be that the ceiling is supported directly by the roof supports.

One of the principal objects of the invention is to provide a ceiling of this construction 10 which provides a smooth, finished under surface which may be decorated directly without the application of plaster, which is easily erected, comparatively light in weight, fireproof, and an excellent insulator.

15 In its preferred form, this ceiling is a thin continuous layer of plastic or cementitious material, which is cast or poured and allowed to set on a bottom form, with a reinforcing net work which is engaged and supported directly by hooks or other fastening means from 20 the floor or roof beam. The plastic material preferably comprises gypsum or other suitable cementing materials, with or without an aggregate of wood shavings or other suitable 25 material, which, when allowed to set, forms a reinforced monolithic slab extending continuously below the supporting members.

In the accompanying drawing, Fig. 1, is a 30 sectional view of a ceiling constructed in accordance with the principles of this invention; Fig. 2 is a plan view of a plurality of supporting members with the reinforcing fabric held in place thereon by the hooks; Fig. 3 is a sectional view showing the forms 35 in place for casting a ceiling of this improved construction; Fig. 4 is a perspective of one of the reinforcing net work supporting hooks; and Fig. 5 shows a twisted tie wire instead of a supporting hook.

40 In carrying out this invention it is desired to provide a continuous ceiling, suspended below or in contact with a number of supports, either the supports for a floor or for a roof. This ceiling being light in weight does not require heavy forms or supports, and being reinforced, it can be supported from the floor or roof beams themselves without any additional truss or supporting means, and when the ceiling is set, it presents a smooth and 45 continuous surface on its underside. Plaster

wallboard which adheres to the layer of plastic material may be used to form a permanent part of the ceiling at the under side thereof, or it may be omitted entirely.

In carrying out this invention a plurality 55 of roof beams or supports 1 are provided in parallel relation to each other, immediately below which the ceiling is desired. A reinforcing net work 2 is suspended directly below these beams 1 by means of hooks 3, which 60 are designed to extend below the net work engaging one or more wires thereof, with the upper ends 4 adapted to be bent around or over the upper edges of the beams 1 so that the net work can be held in place in any desired 65 location or spacing below the beams.

The ceiling proper consists of plastic material 5 containing gypsum or any other suitable cementitious material, which is applied in a thin layer below the beams 1 to imbed the 70 net work 2 therein so that when the plastic material becomes set it will form a continuous or monolithic slab extending below the beams, which may or may not abut them on the 75 underside.

A suitable composition for the plastic material is found to be approximately 100 pounds of gypsum first settle stucco, to which is added about 12 pounds of wood shavings and the necessary amount of water. This 80 plastic mass is poured to imbed the reinforcing net work and is supported in place until the plastic material becomes sufficiently set. It is obvious, of course, that other cementitious materials may be substituted and that 85 other aggregate, such as cinders, sand, or the like, may be included with the plastic material to give it different required properties.

The actual pouring of a ceiling of this kind requires that a bottom form 6 be provided, 90 which is preferably supported directly below the beams 1 at a distance from the lower edge of the supports equal to the thickness of the ceiling desired. This bottom form may be built up of boards or of plaster wallboard 12 95 supported upon boards, and it is supported by cross beams 7 at the bottom, through which are inserted rods 8. The upper ends of these rods are inserted through the form boards, the plaster wallboards, if they are used, and 100

through cross beams 9 placed on top of the supporting beams 1. The ends of the rods 8 are threaded to provide for the nuts 10 and washers 11 by means of which the bottom form 6 is held in place and so that it can be adjusted in height with respect to the lower edges of the beams 1.

The reinforcing 2 may be placed in position below the beams 1 either before or after the bottom form is in place, whichever is more convenient, the hooks or supporting members 3 then applied to the reinforcing and secured to the beams 1, and then the plastic material is poured upon the bottom form and spread in a thin layer to imbed the reinforcing therein. Preferably, the plastic layer is thick enough only to abut or engage the lower edge of the beams 1 so that it is held tightly against the beams by the reinforcing and the supporting means which engages over the top of the beams. The bottom form 6 may also be suspended at a distance below the beams 1, if desired, and a layer of plastic material spread thereon imbedding the net work, entirely below the lower edges of the beams 1, but it is believed preferable to have the ceiling in contact with the beams.

The wallboard 12 may be built up as a part of the bottom form 6, supported loosely by the form boards, or it may be placed upon the bottom form after it is constructed. This wallboard adheres and bonds to the monolithic slab cast upon it and forms a smooth, pleasing, continuous under surface. Either the wallboard surface, or the monolithic slab, if the wallboard is omitted, may be treated as any other wall surface, but as it makes a smooth, finished surface in either form, no further treatment is necessary.

In order properly to space the bottom of the form 6 or the wallboard held thereby below the supporting beams, a number of spacer blocks 14 may be placed at intervals below the beams 1. These blocks prevent the forms from being drawn too close to the beams, and also form a gauge for the thickness of the slab below the beams. The blocks are made of gypsum, or the same material as the slab, preferably wedge shaped, and left in the ceiling, but if desired they may be made of wood or some other material and removed before the ceiling is complete and the openings filled up.

Instead of the hooks 4, a number of fastening wires 13 may be bent around the supporting beams 1, engaging and holding the reinforcing 2, and the ends twisted together, as shown in Fig. 5.

When this monolithic ceiling slab has become sufficiently set or hardened, the bottom form support 6 is removed by disconnecting the rods 8 and removing them. This will leave small holes where the rods have been inserted and these holes are then filled with suitable cement, so that the underside of the

ceiling presents a continuous unbroken surface, the supporting means being invisible from the under side, and there being no joints or contact points with the beams, where cracks are likely to appear.

I claim:

1. In a fireproof ceiling construction, in combination metal beams or channels, wire reinforcing suspended therefrom, hardened plastic cementitious material in contact with undersurfaces of metal beams or channels while embedding the reinforcing material, plasterboard spaced beneath the metal or channel members, and a definite thickness of cementitious slab bounded thereto.

2. In a fireproof ceiling construction, in combination metal beams or channels, a hardened plastic cementitious slab containing embedded wire reinforcing fabric in contact with but suspended therefrom, and governed in thickness by retained spacers disposed between the undersurfaces of the metal beams or channels and the slab undersurface.

3. In a fireproof ceiling construction, in combination metal beams or channels, wire reinforcing suspended therefrom, hardened rehydrated calcium sulphate in contact with undersurfaces of metal beams or channels while embedding the reinforcing material, plasterboard spaced beneath the metal or channel members and a definite thickness of rehydrated calcium sulphate slab bonded thereto.

4. In a fireproof ceiling construction, in combination metal beams or channels, a hardened rehydrated calcium sulphate slab containing embedded wire reinforcing fabric in contact therewith but suspended therefrom, and governed in thickness by retained spacers disposed between the undersurfaces of the metal beams or channels and the slab undersurface.
